United States Patent Office

Des. 187,940

Patented May 17, 1960

187,940

CREAM PITCHER OR SIMILAR ARTICLE

Elmer C. Hughes, Syracuse, N.Y.

Application May 13, 1959, Serial No. 55,888

Term of patent 14 years

(Cl. D44—21)

Fig. 1 is a top plan view;
Fig. 2 is a side elevation; and
Fig. 3 is a perspective view of the cream pitcher showing my new design.

I claim:
The ornamental design for a cream pitcher or similar article, substantially as shown.
